UNITED STATES PATENT OFFICE.

MOTIMORE GREEN, OF PITTSBURGH, PENNSYLVANIA.

MASONRY SPACING AND FACING ELEMENT.

Application filed July 3, 1923. Serial No. 649,296.

To all whom it may concern:

Be it known that MOTIMORE GREEN, a citizen of the United States, residing at Pittsburgh, in the county of Allegheny and 5 State of Pennsylvania, has invented new and useful Improvements in Masonry Spacing and Facing Elements, of which the following is a specification.

The object of the invention is to provide 10 a spacer for the units of brick, cement block, and masonry walls, generally, whereby the joint forming cement may be confined and concealed and a uniform spacing of the masonry units insured and incidentally to 15 provide an element of this type which is adapted also to perform the function of a joint facing member which is susceptible of a treatment in coloring or otherwise which is either in uniformity with or in contrast 20 to the units of the wall or like structure in connection with which the device is used; and with these objects in view the invention consists in a construction and arrangement of parts of which a preferred embodiment is 25 shown in the drawings, wherein:—

Figure 1 represents a portion of a wall made up of bricks or blocks between which are interposed spacing and facing elements embodying the invention.

Figure 2 is a sectional view on the plane indicated by the line 2—2 of Figure 1.

Figure 3 is a detail view of the side or horizontal spacing elements.

Figure 4 is a section on the plane indicated 35 by the line 4—4 of Figure 1.

Figure 5 is a detail view of one of the end spacing elements.

The device consists essentially of a hollow frame 10 of a contour exteriorly which corresponds with the structure in connection with which it is to be used and which, for example, in connection with a flat wall composed of flat faced units such as the blocks or bricks 11 as shown in the drawing, is of 40 rectangular form and is of a thickness which corresponds with the preferred spacing of the units 11 of the structure with its pe-

ripheral edges flush or substantially flush with those of the units to form a joint facing which may be suitably ornamented or may be 50 surfaced to accord or contrast with surfaces of the units. The space bounded by the frame and which is indicated at 12 is adapted for the reception of cement for binding the ornaments of the structure and for 55 proper relation in accordance with the usual practice of seating bricks, building blocks and other masonry units in cement. The facing frame serves to provide a finish for the joints between the units of the structure 60 without the necessity of pointing as in the ordinary practice and under conditions insuring greater durability and of more uniform appearance than is possible under the present practice. 65

Having described the invention, what is claimed as new and useful is:

1. A spacing device for interposition between the adjacent faces of the units of a masonry structure, consisting of a hollow 70 frame bounding a space adapted for the reception of cement for uniting units of said structure.

2. A spacing device for interposition between the adjacent faces of the units of a 75 masonry structure, consisting of a hollow frame bounding a space adapted for the reception of cement for uniting units of said structure, the frame having an exterior contour corresponding with the superficial contour 80 of the structure in connection with which it is used.

3. A spacing device for interposition between the adjacent faces of the units of a masonry structure, consisting of a hollow 85 frame bounding a space adapted for the reception of cement for uniting units of said structure, said frame being peripherally arranged in substantially flush relation with the surfaces of a masonry structure in connection with which it is used. 90

In testimony whereof he affixes his signature.

MOTIMORE GREEN.
